UNITED STATES PATENT OFFICE

2,405,132

RAILROAD JOURNAL BOX

Richard J. Brittain, Jr., Bloomfield, N. J., assignor to General Motors Corporation, Detroit, Mich., a corporation of Delaware

Application March 10, 1944, Serial No. 525,883

14 Claims. (Cl. 105—223)

1

This invention relates to railroad journal boxes and comprises all of the features of novelty herein disclosed. An object of the invention is to provide improved means for mounting a journal box in a car frame. Another object is to provide improved swing link mechanism for supporting a car frame on a journal box. To these ends and also to improve generally upon devices of this character, the invention consists in the various matters hereinafter described and claimed. In its broader aspects, the invention is not necessarily limited to the specific constructions selected for illustrative purposes in the accompanying drawings in which

Fig. 1 is one half a horizontal section on Fig. 2 taken at axle level and one half a horizontal section taken above the yoke.

Fig. 2 is one half an end view and one half a vertical central section.

Fig. 3 is a perspective view of the yoke and associated parts.

Fig. 4 is one half a central vertical section and the remainder a vertical section across the cushioned seat members, portions of the pedestal and of the yoke being broken away.

Fig. 5 is a vertical section across the cushioned seat members, portions of the pedestal being broken away and the yoke being tilted.

Figs. 6, 7 and 8 are sectional views of modifications of the seat members.

Fig. 9 is a perspective view similar to Fig. 3 of a modified construction.

Fig. 10 is a horizontal section of the yoke of Fig. 9.

Fig. 11 is a side view of the yoke of Fig. 9.

Figs. 12 and 13 are views similar to Fig. 5 showing the yoke of Fig. 9 in two positions.

Fig. 14 is one half a horizontal section of Fig. 15 taken at axle level with the other half a horizontal section taken above the yoke.

Fig. 15 is one half an end view of Fig. 14 and one half a central vertical section.

The axle journal 2 has a pair of inner race rings 4 clamped thereon for two rows of rollers 6 which run in an outer race ring or box 8. An outer end cap 10 and an inner end cap 12 are bolted to the box, there being a suitable seal or guard between the inner end cap and the axle. The box is four-sided, each side being flat along the central portion and tapering down slightly towards the ends as at 13, and the four corners of the box are rounded as at 14. A saddle or seat plate 16 rests on the top of the box and has limited rocking movement thereon, its under surface being slightly crowned longitudinally of the

2

axle. The seat plate has its opposite ends curled down as at 18 over the rounded corners 14 of the box to prevent the seat plate from shifting crosswise of the box. To prevent shifting of the seat plate longitudinally of the box, it has depending lugs 20 whose inner faces diverge and are crowned vertically alongside of the flanges on the end caps. Upwardly extending flanges 22 on the seat plate form a channel in which fits the upper cross member 24 of a swinging hanger or yoke which embraces the box, the yoke being rockable with the seat plate on the box, the lugs 20 limiting the rocking movement.

The yoke has flat side legs 26 extending down along the sides of the box and below it, the legs being connected by a cross bar 28 which is spaced from the bottom of the box. The bar 28 has a wavy cross section with depending flanges 30 and it is passed through similarly shaped slots in the

20 yoke legs 26 and welded to them. Gussets 32 are welded to the yoke legs and to the flanges 30, each gusset having a lug 34 bent inwardly along the lower end of the corresponding leg and welded to it. Each projecting end of the bar 28 thus

25 provides a wavy shelf or seat 35 having a central U-shaped concavity 36 and a pair of convexed ridges 38. A compressible cushion or pad 40 conforms to the wavy seat and supports the pedestals 44 of the side frame 42.

30 Each pedestal 44 is of U-shaped section with a flat vertical web 46 alongside the adjacent yoke leg 26. Near the bottom each pedestal has a recess forming a horizontal web or seat 48 of wavy section which rests on the cushion and is

35 a counterpart of the adjacent wavy seat 35. Flanges 50 on the pedestals project downwardly in clearance relation to the flanges 30 so that rocking movement between the yoke and the pedestals is limited. A safety bolt 52 on each pedestal extends below the adjacent seat or shelf 35 to prevent disengagement of the frame and the yoke. A pair of lugs 53 on each pedestal embrace

40 vertically crowned faces on the front and rear end caps of the box to limit relative rocking 45 movement between the pedestals and the box.

If the journal box and axle shift laterally of the side frame to a considerable extent as indicated in Fig. 5, the yoke will rock to an angular position out of the vertical, the yoke and its seat plate 50 16 rocking on the top of the box and the yoke also having a tilting movement with respect to the pedestal seat. The pedestal will of course remain substantially vertical. One of the convex ridges 38 of the seat 35 will rock downwardly away from 55 its corresponding concavity while the other rises,

thus tending to lift the side frame. The weight of the car thus resists abnormal shifting and tends to restore the parts to central position. When the journal box and axle have only a slight shifting movement, the cushion will merely become more compressed at one side than at the other without any resulting lifting.

In the alternative form shown in Fig. 6, steel liners 54 of wavy form are welded to the wavy seats 35 and 48. These conform to each other so that upon any relative tilting of the yoke and the pedestal, one of the convex ridges will separate from its concavity while a sliding and rocking movement occurs at the other side of the center so that the side frame will rise and resist the movement, gravity thus tending to restore the parts to normal position.

In Fig. 7, a pad or cushion 55 is interposed between arcuate seats, the lower seat 35A having a longer radius than the upper seat 48A. The cushion is shown with no load applied. Application of the load will compress the cushion to the greatest extent at the center with the compression decreasing towards the ends. If the yoke 26 tilts, the connected lower seat 35A will tilt likewise but the cushion will increasingly resist the movement. Upon extensive tilting, one of the ends of the arcuate seat 35A may engage the adjacent portion of the pedestal seat 48A and lift the latter.

In Fig. 8, a cushion or pad 56 shown without load applied is interposed between co-operating seats which are composed of straight lines merging with curves. At each side of the center, the lower seat has straight portions 57 which make a slightly smaller angle with the horizontal than the straight portions 58 of the upper seat. When load is applied the cushion will be initially compressed to the greatest extent at the center. Tilting of the yoke 26 will be increasingly resisted by the cushion. The flanges 50A on the pedestal make a similar small angle with the flanges 30A on the yoke 26 and hence substantial tilting of the yoke will compress the depending portions of the cushion.

In Figs. 9 to 15 the yoke has been modified at the sides and bottom. The yoke legs 26A are rigidly connected at the bottom by an upwardly open channel iron 60. This channel iron is secured to each yoke leg by an angle iron 62, by rectangular plates 64 and by trapezoidal plates 66, all welded in place. The channel 60 terminates flush with the outer surfaces of the yoke legs 26A and loosely supports an angle iron 63 which extends beyond the legs to form at each end a seat for a cushion or pad 70 on which rests an angular web or seat 48B of the pedestal 44.

Each yoke leg 26A has a vertical slot 72 which extends upwardly through the top of the leg. Welded to the pedestals are tapering wear plates or spacers 74 which occupy the slots. The spacers are thicker than the yoke legs to prevent the yoke from being pinched and thus prevented from rocking freely between the pedestals and the box. A lug 76 on one side of each pedestal will limit the shifting of the yoke and the box.

Fig. 13 shows the yoke in vertical position and Fig. 12 shows the yoke in tilted position. The angle iron 63 has its legs at 45° to the vertical while the co-operating legs on the pedestal seat 48B make a slightly greater angle with the vertical. Accordingly the load initially compresses the cushion to the greatest degree at the center with less and less compression away from the center. Upon slight rocking of the yoke 26A, the cushion

will offer increasing resistance. Upon ample rocking movement of the yoke and the connected channel, one of the legs of the angle iron will remain on the channel iron which rocks thereon to tilted position and leaves the other leg of the angle iron free as indicated in Fig. 12. Accordingly there is a lifting of the pedestal although the latter remains substantially vertical.

I claim:

1. In a device of the character indicated, a journal box, a yoke embracing the box and rockable thereon, means supported by the yoke and extending beyond the latter to form a supporting seat at each side of the box, a frame having pedestals embracing the legs of the yoke, each pedestal having a seat overlying the supporting seat, one seat having a central concavity between a pair of convex portions and the opposing seat having a substantially matching contour, the seating surfaces being substantially equidistant, and a pad of substantially uniform thickness between the seats.
2. In a device of the character indicated, a journal box, a yoke embracing the box and rockable thereon, means supported by the yoke and extending beyond the latter to form a supporting seat at each side of the box, a frame having pedestals embracing the legs of the yoke, each pedestal having a seat overlying the supporting seat, one seat having a central concavity between a pair of convex portions and the opposing seat having a substantially matching contour to form a pair of fulcrums spaced apart crosswise of the frame for the yoke to tilt upon with respect to the pedestal.
3. In a device of the character indicated, a journal box, a yoke embracing the box and rockable thereon, means supported by the yoke and extending beyond the latter to form a supporting seat at each side of the box, a frame having pedestals embracing the legs of the yoke, each pedestal having a seat overlying the supporting seat, one seat having a concave rounded portion extending crosswise of the frame and the opposing seat having a convex rounded portion spaced from the concave portion, and a pad of substantially uniform thickness between the seats.
4. In a device of the character indicated, a journal box, a yoke rockable on the box and having legs at the sides of the box, a frame having pedestals embracing the yoke, a bar of wavy section extending through and beyond the yoke legs to form a supporting seat at each side of the box, and each pedestal having a wavy seat overlying the supporting seat.
5. In a device of the character indicated, a journal box, a yoke rockable on the box and having legs at the sides of the box, a frame having pedestals embracing the yoke, each leg of the yoke having a supporting seat projecting outwardly therefrom to overlap the pedestal leg, each pedestal having a similar seat overlying the supporting seat and rockable thereon, and each pedestal having a side lug extending inwardly across the edge of a yoke leg and into overlapping relation to an end of the box to limit shifting of the box and the yoke with respect to the pedestal.
6. In a device of the character indicated, a journal box, a yoke rockable on the box and having legs at the sides of the box, means for rigidly connecting the lower portions of the legs, the lower portions of the legs having wavy seats projecting therefrom, a frame having pedestals em-

bracing the yoke, and the pedestals having wavy seats substantially matching the first mentioned seats and supported thereby.

7. In a device of the character indicated, a journal box, a yoke embracing the box and rockable thereon, means supported by the yoke and extending beyond the latter to form a supporting seat at each side of the box, a frame having pedestals embracing the legs of the yoke, each pedestal having a seat overlying the supporting seat, the co-operating seats being of angle form and spaced apart, and a pad of substantially uniform thickness between the seats.

8. In a device of the character indicated, a journal box, a yoke embracing the box and rockable thereon, means supported by the yoke and extending beyond the latter to form a supporting seat at each side of the box, a frame having pedestals embracing the legs of the yoke, each pedestal having a seat overlying the supporting seat, the companion seats being of angle form, a pad of substantially uniform thickness between the seats, the opposing legs of the angle diverging slightly as they proceed away from the apex to apply a decreasing initial load to the pad from the middle outwards.

9. In a device of the character indicated, a journal box, a yoke rockable on the box and having legs at the sides of the box, a supporting member for rigidly connecting the lower portions of the legs, an angular member mounted on said supporting member and projecting through and beyond the yoke legs to form angular seats, a frame having pedestals embracing the yoke, and the pedestals having angular seats substantially matching the first mentioned seats and supported thereby.

10. In a device of the character indicated, a journal box, a yoke embracing the box and rockable thereon, means supported by the yoke and extending beyond the latter to form a supporting seat at each side of the box, a frame having pedestals embracing the legs of the yoke, each pedestal having a seat overlying the supporting seat, the companion seats being spaced apart and extending in a direction crosswise of the frame, the

space between the seats gradually increasing from the middle outwards, and a pad of substantially uniform thickness between the seats.

11. In a device of the character indicated, a journal box, a yoke embracing the box and rockable thereon, each leg of the yoke having an opening alongside of the box, a frame having pedestals alongside of the yoke legs, means for supporting the pedestals on the yoke for relative rocking, and a spacing plate in each yoke leg opening and interposed between the box and the pedestal, the spacing plate being thicker than the yoke leg.

12. In a device of the character indicated, a journal box, a yoke embracing the box and rockable thereon, each leg of the yoke having an elongated opening alongside of the box, a frame having pedestals alongside of the yoke legs, means for supporting the pedestals on the yoke for relative rocking, a spacing plate in each elongated opening and interposed between the box and the pedestal, the spacing plate being narrower than the opening, and the sides of the plate and the sides of the opening being relatively tapered.

13. In a device of the character indicated, a journal box, a yoke embracing the box and rockable thereon, means supported by the yoke and extending beyond the latter to form a supporting seat at each side of the box, a frame having pedestals embracing the legs of the yoke, each pedestal having a seat overlying the companion supporting seat, the companion seats being extended crosswise of the frame and constructed and arranged to support the yoke for tilting with respect to the pedestal about either of two laterally spaced fulcrums.

14. In a device of the character indicated, a journal box having its top unobstructed, a tiltable seat plate covering the top of the box and having downturned portions embracing the box, a yoke supported by the seat plate, a frame having pedestals embracing the yoke, a bar rigidly connecting the legs of the yoke and tiltable therewith, and means providing a rocking engagement between the pedestals and the legs of the yoke.

RICHARD J. BRITTAINE, JR.
